By his Attorney, Houston, Mo.

UNITED STATES PATENT OFFICE.

ALFRED C. REX, OF PHILADELPHIA, PENNSYLVANIA.

MAKING LOCK-SPINDLES.

SPECIFICATION forming part of Letters Patent No. 376,014, dated January 3, 1888.

Application filed October 15, 1886. Serial No. 216,322. (No model.)

To all whom it may concern:

Be it known that I, ALFRED C. REX, a citizen of the United States, residing in Philadelphia, Pennsylvania, have invented certain improvements in the Manufacture of Lock Spindles, of which the following is a specification.

My invention consists of an improvement in the manufacture of spindles for locks, my invention being more especially designed for the manufacture of spindles for the cheap combination-locks to be used in connection with toy safes and similar articles, although my invention may be applied to the manufacture of other spindles.

In the accompanying drawings, Figure 1 is a vertical section of a toy-safe door and part of the frame, showing the manner in which lock-spindles constructed in accordance with my invention may be applied. Fig. 2 is a detailed view, partly in section, of the working parts of the lock with the cover-plate removed. Fig. 3 is a perspective view of one of the notched wheels of the lock, its spindle, and operating-disk. Fig. 4 is a side view showing the manner of turning the groove in the end of the spindle. Fig. 5 is a side view of the spindle after the groove has been turned in it, but before the end has been cut by the die; and Fig. 6 is a view illustrating the manner of cutting the polygonal end of the die.

Referring to Fig. 1, A A represent the walls of the safe, D the door, and E the combination-lock, which is provided with a sliding locking-bolt, d, adapted to engage with the jamb 35 of the doorway or a keeper thereon. In the present instance I have shown the lock as provided with three notched wheels, e, which are adapted to act on the inner end of the bolt d against the pressure of a spring, d'. The 40 outer wheel is mounted on a spindle, F, which is passed through the door and provided on the outside with a suitable operating knob or disk, F'. The spindles of the inner wheels are

made tubular, so as to fit over each other and over the central spindle belonging to the outer wheel, as shown in Fig. 1. The portion of the spindle F on which the wheel is fitted is made many-sided, as illustrated in Figs. 2 and 3, and the central opening of each wheel is made of a shape to correspond, so that the combination 45 of the lock can be readily changed at any time by simply removing the inside cover-plate of the lock, taking the wheels off their spindles and resetting them in other positions.

In order to construct these spindles with the least possible expense and yet with accuracy, I proceed in the following manner: After the spindle has been turned to the proper diameter I cut in each a circumferential groove, f, by means of any suitable cutter, s, as indicated 60 in Fig. 4. The spindle thus formed, Fig. 5, is then put under a die, R, Fig. 6, which cuts at one operation the several sides on its end, these several sides corresponding with the many-sided opening cut by the punches and 65 dies, as usual, in the corresponding wheel e. Owing to the presence of the groove f immediately behind that portion of the spindle on which the straight sides are cut by the die, a good clearance is afforded for the metal in cutting, so that the sides are cut clean and straight. 70

I claim as my invention—

The mode herein described of making lock-spindles with many-sided ends, said mode consisting in first cutting a circumferential groove 75 near the end of the spindle, and then cutting the straight sides on the end of the spindle beyond the said groove by means of a die, all substantially as set forth.

In testimony whereof I have signed my name 80 to this specification in the presence of two subscribing witnesses.

ALFRED C. REX.
